(57) **CLAIM**

The ornamental design for a resistance spot welding electrode, as shown and described.

DESCRIPTION

FIG. 1 is a perspective view of our new design for a resistance spot welding electrode;
FIG. 2 is a front view of the resistance spot welding electrode shown in FIG. 1;
FIG. 3 is a rear view of the resistance spot welding electrode shown in FIG. 1;

FIG. 4 is a top view of the resistance spot welding electrode shown in FIG. 1;

FIG. 5 is a bottom view of the resistance spot welding electrode shown in FIG. 1;

FIG. 6 is a left side view of the resistance spot welding electrode shown in FIG. 1;

FIG. 7 is a right side view of the resistance spot welding electrode shown in FIG. 1; and,

FIG. 8 is a cross-sectional view of the resistance spot welding electrode shown in FIG. 1.

The evenly-spaced broken lines illustrate portions of the resistance spot welding electrode which form no part of the claimed design. The dash-dot-dash-type broken line illustrates the boundary of the claim and forms no part thereof.
